GEORGE GILLESPIE AND WILLIAM W. GILLESPIE, OF WEST VIEW, PENNSYLVANIA.

THUMB-TACK TOOL.

1,369,420.

Specification of Letters Patent. Patented Feb. 22, 1921.

Application filed March 22, 1920. Serial No. 367,944.

To all whom it may concern:

Be it known that we, GEORGE GILLESPIE and WILLIAM W. GILLESPIE, residing at West View, in the county of Allegheny and 5 State of Pennsylvania, both citizens of the United States, have invented or discovered certain new and useful Improvements in Thumb-Tack Tools, of which improvements the following is a specification.

10 Our invention consists in a tool for carrying, applying, and removing thumb tacks. It is illustrated in the accompanying drawings.

Figure 1 is a view of the tool in longitudinal medial section; Fig. 2 is a view in plan, the top wall being, for the greater part of its length, broken away; Figs. 3 and 4 are views in plan and to larger scale, showing a portion of the tool. In these 20 two figures also the top wall is in part broken away, to more clearly illustrate in its alternate positions the feed valve. Fig. 5 is a view in transverse section, and to somewhat greater scale still than Figs. 3 and 4. The plane of section is indicated at 25 V—V, Fig. 4.

As a container and carrier the tool consists essentially of an elongate barrel 1, of suitable width and depth to receive a thumb 30 tack, within which is a slotted web 2. The arrangement of the thumb tacks within this container or carrier will be perceived at a glance at the drawings. The thumb tacks may, as will presently more clearly appear, 35 be introduced at the front or working end, the end which terminates in holder 3, or they may be introduced at the rear end, and with the latter alternative in mind, the rear end is shown to be closed with a hinged cap 10 40 which may at will be swung to open position.

As an instrument for applying thumb tacks, the tool includes essentially a bifurcated holder 3, between the furcations of 45 which the thumb tack to be applied is held, and an overhanging flexible member 4, which aids in bringing the thumb tack to position in the holder, and prevents falling of a thumb tack from the tool when brought 50 to position, and through which the pressure of the thumb of the user may be exerted, to drive the tack to place.

As an instrument for removing thumb tacks, the tool is essentially a claw, consisting 55 of the bifurcated tack-engaging member 3, the fulcrum heel 5, and the handle 1.

These functions of the tool in its several aspects are accomplished in the following manner: The magazine 1 becomes the handle of the tool when used in application or removal of a thumb tack; the member 4 which guides a thumb tack to be applied to position between the furcations of holder 3 and retains it there and which then serves as a flexible member through which the pressure 60 of the thumb of the user may be exerted, to drive the tack, is conveniently a prolongation of the upper wall of the container 1; and the same bifurcated member 3 serves both as the holder of a tack to be driven 65 and as the claw by which a driven tack is engaged when it is to be removed. It is structurally integral with the container, and the cleft between its forks is, as best shown in Fig. 2, a continuation of the slot in web 2. 70 75

In order to render this member 3 adequate to its intended purposes, the slot is preferably narrowed (cf. Fig. 2) till the opposite edges normally meet, and, further, the neck 80 by which these forks of member 3 are united to the body of the tool are so far diminished in thickness that the flexibility and resiliency of the material may permit of the spreading and closing again of the slot 85 through the member 3, to allow passage of, and yet suitably to control the passage of, a thumb tack. This flexibility may be localized, if preferred, mainly in one of the two furcations; and provision to bring such a localization about is indicated in Fig. 2 of 90 the drawings in the hinge 6, which it will be understood is spring-backed.

It remains to explain the valve or gate 95 through which thumb tacks are fed one by one, at the will of the user, from or to the magazine. Across the body of the tool, and at the base of the bifurcated member 3 (which, conveniently, is a solid casting) and adjacent the end of the magazine chamber, is formed a slideway for a block 7. This 100 block 7 occupies the lower portion of the tool. A web-like portion of member 3 extends above this block 7 (as is best indicated in Fig. 1), and through this web extends, as already explained, the slot which 105 forms a continuation of the slot in web 2. Across block 7 in oblique direction extends a slot which, in the opposite positions of the block shown in Figs. 3 and 4, is continuous with the longitudinal slot through web 2 110 and member 3, first on one side (the magazine side) and then on the other side (the

delivery side). Normally block 7 is retained at one end of its slideway (the position say of communication with the magazine—it manifestly might be either position) by a spring 8, and it is shifted to its opposite position against spring tension, by pressure upon a knob 9.

Operation is simple. Suppose that the magazine contains one or more thumb tacks 10 and that a thumb tack is to be applied. The instrument is inclined so that the contents of the magazine slide along the slot in web 2, toward gate member 7. The contents of the magazine come to rest with the shank 15 of the advance tack *a* extending just within the oblique slot in member 7. The superposition of longitudinal and oblique slots brings the tack to rest at this point, as is clearly indicated in Fig. 3. It should here 20 be observed that the thumb tacks are by their very shape so spaced within the magazine that their shanks, which extend through the slot in web 2, are separated at minimum intervals equal approximately to 25 half the diameter of the heads. Accordingly, the shanks of two tacks cannot come at one time into the oblique slot in member 7.

When the contents of the magazine have 30 been brought to this position, block 7 is shifted, by pressure on knob 9. The parts then assume the position shown in Fig. 4, and it will be observed that the thumb tack *a* has, by the shifting of the slide (its shank 35 extending through both the longitudinal slot in member 3—the web portion thereof, above block 7—and into the oblique slot in block 7), been carried to the opposite side of the slide, whence it advances freely along 40 the slot toward the free end of member 3. Caught lightly in the narrow throat in the slot in member 3, in the position indicated in Figs. 1 and 2, the tack is applied at the proper point over a drawing board, and 45 then the one who is using the tool applies it, by pressing down upon member 4. The tool is then easily drawn away, the flexible bifurcated member 3 opening sufficiently to allow the shank of the thumb tack to escape. 50 Thereafter, if need be the tack may be driven further to place.

To remove a tack, the tool is applied as a claw, the bifurcations of member 3 wedging under the head of the tack and raising it. 55 A slight forward thrust of the tool will then bring the shank of the tack beyond the narrow place in the claw, and to the position indicated in Fig. 2. Meanwhile, a certain leverage exerted by turning the tool on its 60 heel 5 (which rests on the drawing board) will have released the tack, so that it comes away with the tool. The tool is then inclined with its magazine end downward, and the block 7 is shifted inward; the tack then 65 comes to the position indicated at *a*, Fig. 4.

Release of pressure upon knob 9 allows block 7 to resume under spring pressure its normal position—that shown in Fig. 3—and in so doing the block carries the tack rearward into the magazine. 70

In the ensuing claims we shall define the essential features of our invention. In other respects, the showing of the foregoing specification is exemplary; our invention will be employed if these essential features 75 be employed, whatever be the variation in other respects from our specification.

We claim as our invention:

1. A thumb-tack tool including in its structure a magazine member and a bifurcated positioning member adapted to engage the shank of a tack when being applied and removed, the furcations of said positioning member being flexible one with respect to the other, whereby a space between them 85 normally less than the thickness of the shank of the tack may widen, and the space between the furcations being in communication with the magazine member, substantially as described. 90

2. A thumb-tack tool including in its structure a bifurcated positioning member adapted to engage the shank of a tack when being applied and removed whose furcations are flexible one with respect to the other, whereby the space between them normally less than the thickness of the shank of the tack may widen, and a flexible plate overhanging said positioning member, substantially as described. 95

3. A thumb-tack tool including in its structure a magazine chamber, a slotted web extending throughout said chamber, a bifurcated positioning member, the space between whose bifurcations is continuous with 105 the slot in the said web, and a gate member underlying said slotted web at a point adjacent said positioning member and itself provided with a slot angularly disposed when the parts are assembled with respect 110 to the slot in the web above, said gate member movable transversely of said web and in the range of such transverse movement bringing successive portions of the slot formed in it into alignment with the slot in 115 the web above.

4. A thumb-tack tool including in its structure a magazine chamber, a slotted web extending throughout said chamber and prolonged at one end beyond said chamber to 120 constitute a bifurcated positioning member, and a gate member underlying said slotted web and itself provided with a slot angularly disposed when the parts are assembled with respect to the slot in the web above, said gate movable transversely of 125 said web, and in the range of such transverse movement bringing successive portions of the slot formed in it into alignment with the slot in the web above. 130

5. A thumb-tack tool including in its structure a magazine member consisting of a surrounding casing and an internal slotted web, a bifurcated positioning member formed integral with said web and a flexible plate overhanging said bifurcated positioning member and formed integral with said casing, substantially as described.

In testimony whereof we have hereunto set our hands.

GEORGE GILLESPIE.
